LOCKING DEVICE FOR FIRE CONTROL
MECHANISM

Ivan A. Swidlo, Springfield, Mass.

Application May 24, 1948, Serial No. 28,963

2 Claims. (Cl. 89—149)

(Granted under the act of March 3, 1883, as
amended April 30, 1928; 370 O. G. 757)

1

The invention described in the specification and claims may be manufactured and used by or for the Government for governmental purposes without the payment to me of any royalty thereon.

This invention relates to a device for locking the firing mechanism of an automatic firearm when the breech bolt is in the partially locked or unlocked position.

In certain firearms no adequate provision is made to insure that the firing mechanism will remain safely cocked when the breech block or bolt is in the partially unlocked position. The dangers of premature ignition, such as when the bolt is in the partially unlocked position, are well known to those skilled in the art, for not only may the firearm be seriously damaged but injury to the shooter as well may be experienced.

Accordingly it is an object of this invention to provide a device to lock the fire control mechanism of an automatic firearm to prevent premature discharge of the firearm when the bolt is in the partially locked position.

A particular object of this invention is to provide a locking device for a fire control mechanism of a modified Garand type firearm.

The specific nature of the invention as well as other objects and advantages thereof will clearly appear from a description of a preferred embodiment as shown in the accompanying drawings in which:

Fig. 1 is a fragmentary side elevational view of a firearm showing the fire control locking device with the breech elements in the battery position.

Fig. 2 is a view similar to Fig. 1 but showing the operating rod moved rearwardly just prior to unlocking the firearm bolt.

Fig. 3 is a fragmentary front end view of the firearm receiver showing the manner of securing the support member to the receiver.

Fig. 4 is an enlarged detail perspective view of the firing bar lock.

In Fig. 1 there is shown in assembled relation a receiver 10, a barrel 11, an operating rod 12, a bolt 47 and a spring biased hammer 13 of the well known U. S. rifle cal. .30 M1. The firing mechanism of such rifle has however been modified to fire either semi-automatic or full automatic fire. Such is largely accomplished by a firing bar 14 mounted on the side of receiver 10 as shown in Fig. 1 for limited longitudinal reciprocating movement. An upstanding lug 15 is provided on the forward end of bar 14 which is engaged by a forwardly facing surface 16 pro-

vided on operating rod 12. A longitudinally disposed elongated hole 17 is provided on the forward end of bar 14 and a headed pin 18 passing through such hole is secured to receiver 10. Thus bar 14 is secured to receiver 10 at the forward end for limited longitudinal movement.

The rear end of bar 14 is pivotally supported by a link 19. The lower end of link 19 is pivotally secured to one of a pair of depending lugs 20 of receiver 10 while the upper end of link 19 is pivotally secured to bar 14 by a pin 21. Hammer 13 is pivotally secured to depending lugs 20 by a transverse pin 22. A stud 23 is secured to hammer 13 as shown in Figs. 1 and 2 and such stud 15 is provided with a sloped surface 24. The extreme rear end of bar 14 is provided with a correspondingly sloped surface 25 which is engageable with surface 24 as shown in Fig. 2 and as will be later described.

20 A lug 29 on bar 14 straddles one of the lugs 20 of receiver 10 thereby securing such bar against sideways displacement. A spring 26 longitudinally disposed in a hole 27 provided in the rear end of bar 14 biases a plunger 28 forwardly which bears against lug 20 of receiver 10 thereby producing a rearward force on bar 14 which tends to maintain bar 14 against operating rod 12 as shown in Fig. 1.

Only the handle portion of operating rod 12 30 is illustrated and such handle portion includes a cam slot 30 which is engageable by a bolt lug roller 31 of bolt 47. Cam slot 30 is provided to effect rotation of the firearm bolt for unlocking thereof after the firing of a cartridge.

35 The above elements of the firearm are all conventional and well known in the art and are so described in order that the workings of this invention about to be described can be more readily understood and appreciated.

40 To insure that firing bar 14 will engage stud 23 to secure hammer 13 in the cocked position when the bolt 47 is only partially locked, a firing bar lock 32 is provided. Such lock comprises a rod-like member 33 having a head portion 34. Head portion 34 is formed integral with rod-like member 33 and is disposed at an obtuse angle as shown in Fig. 4, while the other end of rod-like member 33 is sloped as shown at 35. A forwardly and upwardly sloping partial hole 36 is provided 45 in the side of receiver 10 which communicates with cam slot 30 provided in operating rod 12. Firing bar lock 32 is inserted in hole 36 so that the sloped end 35 of rod-like member 33 can be engaged by a correspondingly sloped corner 37 provided on the lower forward edge of cam slot 50 55

30 to depress such lock as will be later described. A spring-like friction device 46 is longitudinally disposed on rod-like member 33 and is suitably secured thereto. Such device is utilized to retain lock 32 in hole 36 when the firearm is disassembled to prevent loss thereof.

A support member 38, which is essentially a pin, is secured to receiver 10 as by riveting as shown at 39 in Fig. 3 and is provided to support the rod-like member 33 of firing bar lock 32 not fully supported by hole 36. Firing bar 14 is cut away as shown at 40 to accommodate support member 38. The rear surface of cut away portion 40, as shown at 41, is shaped to be engaged by head portion 34 of lock 32.

Hammer 13 is held in the cocked position in addition to the firing bar, as will be later described, by a trigger 42 having a sear engaging end 43 engageable with a sear shoulder 44 provided on the end of hammer 13. The remainder of the trigger mechanism is not shown because such mechanism forms no part of this invention and the workings thereof are well known to those familiar with the U. S. rifle, cal. .30 M1. However, it is pointed out that the trigger mechanism herein shown does not operate in exactly the same manner as only one hammer engaging lug is utilized, whereas in the aforementioned firearm two hammer engaging lugs are employed.

The operation of the firing bar is substantially as follows: Starting from the partially closed battery position as shown in Fig. 2, surface 18 of operating rod 12 as shown in Fig. 1, will engage with lug 15 on the forward movement of the firing bar 14. In such position trigger 42 is being squeezed and its sear engaging end 43 is out of engagement with sear shoulder 44. Therefore, in its forward movement, operating rod 12 which is actuated by a spring as known in the U. S. rifle, cal. .30 M1 will pull firing bar 14 forward and with this movement will disengage sloped surface 25 from stud 23 of the hammer 13, which permits spring biased hammer 13 to strike the firing pin (not shown). When hammer 13 is in the cocked position and bolt 47 is locked as shown in Fig. 1 and the operating rod 12 moves rearward, surface 37 in cam slot 30 engages the sloped surface 35 of lock 32 as shown in Fig. 2, thereby forcing lock 32 downwardly into opening 40 and simultaneously the head portion 34 of lock 32 engages the rear surface 41 of the opening 40 in bar 14. Simultaneously with retraction of operating rod 12, the sloped surface 25 of bar 14 has been forced onto sloped surface 24 of stud 23 of hammer 13, depressing hammer 13 slightly. With forward sloped surface 35 of lock 32 covered by bottom surface 37 of the operating rod 12, the sloped surface 25 of firing bar 14 will remain in engagement with stud 23 and prevent accidental or premature release of hammer 13 while bolt 47 of the firearm is in the partially locked position.

The above operation assumes that the hammer 13 has been cocked by a previous reciprocation of the firearm bolt 47. The operating rod 12 throughout its entire recoil stroke bears against the upper sloped surface of lock 32 projecting through hole 36 to maintain the head portion 34 in contact with bar 14 until such time as operating rod 12 returns to battery position whereupon surface 16 of rod 12 contacts lug 15 of bar 14 to carry such bar forwardly thereby removing sloped end 25 from stud 23 whereupon the hammer may be released for firing the cartridge.

As firing bar 14 is moved forwardly, the rear end of such bar is pivoted downwardly a slight

amount through the connection of link 19 so that sloped end 25 may break cleanly from stud 23 to insure a better releasing condition. Also when bar 14 is returned to its forward position, the surface 41 of such bar being in contact with head 34 of lock 32, forces the rod-like member 33 forwardly and upwardly into cam slot 30 as operating rod 12 goes into battery position.

Lock 32 is of primary importance when the firing mechanism is set for semi-automatic fire as in such selection of firing it is not desired to release the hammer until the proper moment as selected by the operator. Accordingly it is highly desirable that means be provided to positively

15. hold the hammer in the cocked position until its release is desired by the shooter. The firing bar lock of this invention definitely provides that the hammer will be positively held in the cocked position by means of the firing bar 14 until the bolt is fully locked.

In full automatic firing, the firing lock 32 will insure that the hammer does not go forwardly prematurely to discharge a cartridge before the bolt has time to become fully locked to the receiver. The operation as above described applies to automatic firing as well as for semi-automatic firing. The only difference between the two is that the sear engaging end 43 of trigger 42 is held out of engagement with the hammer 13 for as long as it is desired to fire automatically.

It may thus be seen from the foregoing description by those skilled in the art that there is here provided an unique locking arrangement to insure that the firing mechanism of an automatic rifle of a type to which this invention may be applied is in a safe position until the breech elements are securely locked. Such device is of sturdy construction and simple and positive in operation thus insuring long life with a minimum replacement of component parts.

I claim:

1. In a firearm, a receiver, a breechbolt reciprocable in said receiver between battery and retracted positions, an operating rod having a rearward end reciprocable in said receiver from a first forward position for positively holding said bolt in locked battery position rearwardly toward a second position unlocking and freeing said bolt for movement to retracted position, a hammer mounted in said receiver for pivotal movement between cocked and firing positions, a firing bar longitudinally movable in said receiver between first and second position, interengaging means between the rearward end of said firing bar and hammer, when the bar is in its said second position, to positively hold said hammer in cocked position, interengaging means between the forward end of said firing bar and said rod, positively moving said bar to first position to free said hammer by and in response to reciprocation of said rod into full first position, an upwardly-and forwardly-extending guide means in said receiver positioned between said rod and bar, a firing bar lock slideable in and along said guide means from a first position wherein the upper end of said lock is disposed in the path of said rod, to a depressed position clear of said rod, and interengaging means between said bar and lock moving said lock to its said first position by and in response to movement of said bar to its said first position, said rod moving said lock and thereby said bar to their said second positions to hold said hammer cocked by and in response to a predetermined initial movement of said rod from its said first position.

2. The firearm recited in claim 1, said rod having a portion which, on initial movement of said rod from first position, cams said lock into its said second position and holds the same in said second position during recoil and counterrecoil of said breechbolt, whereby said bar is moved into second position to positively hold said hammer cocked until said breechbolt has returned to and been fully locked in battery position.
